NECKTIE

Henry Naftali and Valentine Naftali, Bronx,
N. Y., assignors, by mesne assignments, to
Dimple Tie Corporation, New York, N. Y., a cor-
poration of New York

Application March 10, 1938, Serial No. 195,038

10 Claims. (Cl. 2—146)

The present invention desirably relates to neckties of the four-in-hand type, but is not necessarily restricted thereto as will become apparent. It has been found desirable with some persons who use four-in-hand ties, and with those who display such ties in tied position in show windows, to cause a visible depression in the face material of the tie itself, which depression is located just below the cross-over portion of the knot of the tie and is usually located mid-way between the side edges of the tie and extends downwardly, to create a neat and more or less ornamental or dressy appearance. In the case of 10 shops which have such ties on display in their tied condition, the window or other dresser takes pains to provide such an ornamental appearance. Four-in-hand ties have been marketed which do not require as much painstaking adjustment to obtain the depression, inasmuch as the ornamental depression is preformed, or is intended to be caused to be formed, in the knot portion of the tie so as to appear at a point just below the cross-over portion of the knot, but if care is not taken to regulate the lengths of the ends of the tie, or if separate indicating means are not provided, such depression will not be located at the exact point desired, but will be within the knot itself and thus hidden from view, or be way down below the knot. However, such depressions in 15 former ties only appear as small dents, each located at a restricted spot in the tie intended to appear below the knot, and great care must be taken in tying and adjusting the tie.

Under the present invention we overcome the objections referred to, and the means for producing the depression extends in the length of the tie, so as to primarily begin the desired depression at a point in the tie adjacent the upper edge of the cross-over portion of the knot, so that when the main or display end or front portion of the tie is inserted back of the cross-over portion and drawn down to neatly form the completed knot, the desired ornamental effect follows and appears below the cross-over portion of the knot.

Therefore, the improved ties of the present invention are desirable because painstaking efforts are not required in order to create the ornamental effect, inasmuch as the one who ties the tie has means available within the tie itself which do not require that in the first instance the tier of the tie see that the ends are in a definite position relative to each other before tying the tie, or that the tie is so tied as to cause a small dent or depression to appear just below the knot, with no continuation of the depression entering upwardly

5 into or through the knot. If the tier of the improved tie takes a little precaution to have the knot occur in its own intended zone having the improved means located primarily in the position above stated, the chances are that the desired ornamental effect will be created without failing in the attempt.

With these and other objects in view our invention consists of certain novel features to be hereinafter described and then claimed with reference to the accompanying drawings showing three of numerous ways in which the invention may be accomplished.

In the drawings

Fig. 1 is a perspective view illustrating a collar together with a four-in-hand tie, embodying the present invention, tied so as to create the desired ornamental appearance;

Fig. 2 is a plan of one improved form of a four-in-hand tie, partly broken away, such tie being 20 right side out, but folded at right angles to the position in which the tie takes when it is finished, thus showing an intermediate step in the procedure of making it that way;

Fig. 3 is an enlarged transverse section on line 25 3—3, Fig. 2;

Fig. 4 is a single line or skeleton cross-section corresponding to Fig. 3, but not attempting to illustrate the fabric as such, so as to more clearly illustrate this stage in the making of the complete tie;

Fig. 5 is a transverse section on the line 5—5, 30 Fig. 8, showing the tie after it has resumed its condition for use as a tie;

Fig. 6 is a similar skeleton view to Fig. 4, except that it also may be considered as a section on line 5—5;

Fig. 7 shows a completed tie, partly broken away, and seen towards its back portion, parts being indicated in broken lines;

Fig. 8 is a view similar to Fig. 7, except that the tie is here shown as viewed towards its front portion;

Fig. 9 illustrates those portions of the improved tie which are located adjacent the ultimate knot 45 of the tie, and indicates how the depression of the present invention may be first generated before the wide front portion of the tie is inserted back of the cross-over portion of the knot, parts being indicated in broken lines;

Fig. 10 is an exaggerated single line or skeleton view taken on line 10—10, Fig. 1, to show the depression in the front portion of the tie;

Fig. 11 is an exploded diagrammatic view to illustrate a portion of the method used in making the ties of Figs. 7 and 8;

Fig. 12 is a back view of the front portion of a tie showing a modified construction;

Fig. 13 is an exploded diagrammatic view to illustrate more clearly the manner of making the construction shown in Fig. 12;

Fig. 14 is an enlarged transverse section on the line 14—14, Fig. 12;

Fig. 15 is a single line or skeleton view corresponding with the section in Fig. 14;

Fig. 16 is an enlarged detail view to show how the display fabric of the tie may be caught by a blind stitch;

Fig. 17 is another slight modification of what is shown in Figs. 7 and 8;

Fig. 18 is a transverse section on the line 18—18, Fig. 17, and corresponds more or less with Fig. 10; and

Fig. 19 shows another modification in skeleton outline.

Referring to Fig. 1, in particular, the tie 20 may be composed of fabric or other material which is desirable for neckties. The finished knot 21 is preferably caused in the usual way by the one who ties the tie, such tie having the wide front portion 22 which is suspended below the knot. A novel ornamental depression tuck or fold 23 is shown as protruding into view at a point below the knot 21, and is also seen in Fig. 10. Referring to Figs. 2, 7 and 8, the wide front portion 22 of the tie is fully shown, and a portion of the narrower part 24 of the tie at the opposite end thereof is shown.

The improved tie is preferably provided with a woven fabric lining 25, and, when it is, the lining is preferably resilient or elastic and cut on the bias, and may be connected with the body portion of the tie by a longitudinal line of loose stitching 26. When such a lining 25 is employed in the former practice it is usual to have the stitching 26 extend close to the outside of the seam of the tie material, as shown in Fig. 7, but that is not always necessary. The present invention preferably relates to a tie provided with a resilient lining such as described, as that is a construction now widely on the market, although the invention is not restricted to such type of four-in-hand ties.

Referring to Fig. 9, the desirable depression 23 may be caused by starting it from the point of generation indicated by 23a at the top of said figure. One way of obtaining such effect will now be described.

A tie is flattened out as shown in Fig. 2, but to a position which is at right angles to the tie itself when it is ready for use, that is to say, the tie is folded lengthwise and flattened out so that the loose stitching 26 may if desired be located directly adjacent one edge of the so flattened out tie. In any event the so folded tie will have folds to each side of the original fold lines of the tie. The tie is now subjected to the operation of a suitable stitching machine, readily attainable, which makes a line of stitching 28 shown in Figs. 2 to 11 inclusive. It is preferred to do this stitching by machine, although it can be done by hand, and the thread to provide the stitching 28 may have a knotted end 29 shown in Fig. 2. The object is to make the stitching 28 preferably loose in the tie and lining, and it will be seen from Fig. 3 that it extends through all of the material and along lines adjacent the fold in the back of the tie. In Fig. 2 the aforesaid stitching 26 is omitted for the sake of clearness and to avoid confusing it with stitching 28. However, there might not be any stitching 26 at 75

all in the tie. The stitching 28 preferably extends along a reasonable length of the wide front portion 22 of the tie so that it will occupy a part or all of the zone of that portion of the knot which is under the cross-over portion 27 of the knot after the tie has been adjusted. If desired the stitching 28 may only occur at the top of the knot portion or may run for the entire length of the tie.

In the embodiment of the invention shown, it is preferred to designate the stitching 28, if it is a loose stitching, as a gather-up thread inasmuch as it preferably is a loose one to form a gather or tuck, for reasons to be explained. After the stitching 28 has been made in the tie, the tie is again flattened out to the ultimate finished shape which it has when it is ready for use, that is, it is flattened out to a position which is at right angles to the position shown in Fig. 2. The tie will now have the condition shown in Figs. 7 and 8, and, as the thread or stitching 28 is preferably loose, the second flattened out position can be readily assumed, and then the tie has a back portion 30 (Fig. 7) and in the construction shown 25 the seam 31 will extend along the back longitudinally of the tie. The front part 32 of the fabric is the part of the tie which is used for display.

When the tie is flattened out as in Fig. 7, the thread or stitching 28 will provide spaced stitches 33 extending longitudinally of the back, but arranged in alternation at opposite sides of the actual exposed seam 31 of the tie unless the seam is at the edge of the tie or elsewhere. The tie will also have through stitches 34, Fig. 11, that is, 35 stitches which pass through the thickness of the tie, but, as shown, through the back portion of the tie, such stitches connecting the back 30 with the lining 25. The tie will also have transverse stitches 35, as shown in Fig. 8, which are over the lining 25. Hence the through stitches 34 will be at opposite sides of an imaginary line centrally along the tie; as shown, however stitches 34 are at opposite sides of the stitching 26 which connects the tie with the lining. Obviously the 45 stitches 35 may also pass into or be tacked only to the inner surface of the front part 32, in the manner of blind stitching.

The direction in which the stitching preferably runs, when caused by a sewing machine or by hand, is designated by the arrows in Fig. 11 which is an exploded view to graphically illustrate the preferred position of the stitches 33, 34 and 35 with respect to such imaginary center line. As the stitching preferably is loose, it does not interfere with the flattening out of the tie into the position shown in Figs. 7 and 8, and if required the tie may thereafter be pressed or ironed. In this form of the invention where a gather-up loose stitching 28 is utilized, it is assumed in Fig. 50 that the tie is being tied to form an ultimate knot. When a four-in-hand tie according to this construction is tied without having finally passed the front portion 22 underneath the cross-over or turned portion 27, the said front portion 22 will 55 be in front of the cross-over portion 27. The mere weight of the front portion of the tie will then cause the novel ornamental depression or fold 23 to be generated or start to appear at 23a in a partially formed condition. When the front portion 22 of the tie is inserted back of the cross-over portion 27 shown in broken lines and the same pulled down so as to form a knot in the usual manner, the depression 23 is formed by gathering up the material of the lining 25 through the medium of the loose thread or stitching 28

to form a preliminary depression. This causes a complementary depression 23 to be formed in the longitudinal central portion of the tie, and the ornamental part of the depression 23 appears visually below the knot. The result is obtained in this form of the invention by reason of the fact that the loose thread or stitching 28 is so acted upon as to draw more or less together the through and through stitches 34 which lie at opposite sides of the stitching 26 for the lining and to gather up the material. In practice the result mentioned slightly occurs, whether or not the lining 25 is tacked or connected with the inner surface of the front or face of the tie portion 22 by means of stitching 28.

The critical point for generating the depression below the knot is at the location 23a, and it is a fact that if a preformed depression be made in the tie only at a point corresponding with 23a but underneath the face material of the tie the full length of the depression will be started from such point and traverse downwardly back of the cross-over 21, the lower end of the depression 23 appearing as a neat ornamental effect below the knot.

Referring to Figs. 12 to 16 inclusive a modification is illustrated wherein the face portion 37 of the tie at its inner surface material is slightly tacked to the inner parts of the tie. The tie lining 38 is placed between the back 36 and the front portion 31 of the tie. A line of stitching 39 may be used, and if it is used it is stitched into the tie in similar manner to that described with respect to Figs. 2, 3 and 4. Blind stitching 40 preferably is caused to pass through and into the material of the tie while the tie is in the position shown in Fig. 12. Here the object is to cause portions of the stitches 40 to pass across the back 36 of the tie and to pass through the back 36 and the lining 38 and into only the inner surface of the front or face 31 of the tie so that they are not visible on the actual front face of the tie to mar the appearance thereof. When a tie so constructed is adjusted to form a knot therein, these blind stitches will cause a depression to be formed in the visible front part of the tie and within the knot. Enlarged Fig. 16 illustrates how the blind stitching loops at 41 into and is tacked over the inner surface material of the front of the tie. If desired, the stitching 39 alone may be so tacked to the inner surface material.

Figs. 17 and 18 show another modification, Fig. 18 being exaggerated for the sake of clearness. Here the lining only is shown. The stitching 43 corresponds to the stitching shown and described with respect to Figs. 2 to 11 inclusive. Similar stitching 44 and 45 is respectively located at opposite sides of the line of stitching 43 and is of the same character as stitching 43. With such modification the desired depression or gathering also may be assured.

Another modification is shown in Fig. 19 which is a single line or skeleton view made in similar fashion to Fig. 6 and aforesaid figure represents another type of necktie wherein the fabric or material of the back 46 has wide inturned portions 47, 48 lying between the back and the lining 49. Stitching 50 similar to stitching 28 is made in the tie so as to pass through the thicknesses of the back 46, inward portions 47, 48 and lining 49, the stitching going only through three thicknesses.

It is obvious that in any event a preformed depression may be made in the knot forming portion of the tie to produce the desired ultimate effect. The many ways in which this may be done will be apparent to those skilled in the art, and we do not limit the invention, except as defined by the scope of the appended claims.

5 What we claim as new is:

1. A stretchable necktie of the four-in-hand type having stitching disposed in the knot forming area thereof for automatically forming a dimple in the necktie when it is made up into a knot, said dimple extending from within the knot to a point below said knot, said stitching comprising loops disposed transversely of the longitudinal axis of the necktie, said transverse loops being interconnected and facing the front 10 part of the necktie.

2. A stretchable necktie of the four-in-hand type having stitching disposed in the knot forming area thereof for automatically forming a dimple in the necktie when it is made up into a knot, said dimple extending from within the knot to a point below said knot, said stitching comprising longitudinal rows of loops on one 20 side of the material, said rows being spaced from each other across the width of said necktie, and 25 loops on the other side of the material transversely disposed with respect to the longitudinal axis of the necktie.

3. A stretchable necktie of the four-in-hand type having stitching disposed in the knot forming area thereof for automatically forming a dimple in the necktie when it is made up into a knot, said dimple extending from within the knot to a point below said knot, said stitching comprising longitudinal rows of loops, said rows being spaced from each other across the width of 30 said necktie and interconnected.

4. A necktie of the four-in-hand type having stitching disposed in the knot forming area thereof for automatically forming a dimple in the necktie when it is made up into a knot, said dimple extending from within the knot to a point below said knot, said stitching comprising longitudinal rows of loops located at the back of the necktie, said rows being spaced from each other 40 across the width of said necktie, said spaced rows of loops being formed from a single continuous thread, said thread being under tension and permanently fixed at opposite ends thereof to said necktie whereby to preform a longitudinal ridge therein to aid in the automatic forming of 45 said dimple.

5. In a necktie of the four-in-hand type having a tubular fabric casing and a stretchable lining disposed within said casing, stitching disposed in the knot forming area of said lining for automatically forming a dimple in the necktie when it is made up into a knot, said stitching comprising longitudinal rows of loops and interconnecting transverse loops, said longitudinal 55 rows being spaced from each other across the width of the lining and disposed on the opposite side of the lining from the transverse loops.

6. A necktie including an end portion and a resilient lining therein yieldably extensible longitudinally of the necktie, said lining having a row of stitching extending generally along the axis of the lining and slidably passing therethrough, said stitching comprising successive longitudinally extending stitch sections and transverse 60 stitch sections connecting the ends of adjacent longitudinal sections, said transverse stitch sections being on the front face of the lining.

7. A necktie including a casing yieldably extensible longitudinally of the necktie, said casing having a row of stitching extending general- 75

ly along the axis thereof and slidably passing through the longitudinal edges of said casing thereby connecting the same and forming a tube, said row of stitching being disposed in the rear portions of the necktie, said stitching comprising successive longitudinally extending stitch sections and transverse stitch sections connecting the ends of adjacent longitudinal sections, said transverse stitch sections being within said tube adjacent the rear surface of the front portion of said casing.

8. A stretchable necktie of the four-in-hand type having a resilient lining therein yieldably extensible longitudinally of the necktie and having stitching disposed in the knot forming area thereof for automatically forming a dimple in the necktie when it is made up into a knot, said dimple extending from within the knot to a point below said knot, said stitching passing through said lining and comprising loops crossing the longitudinal axis of the necktie, said last mentioned loops being interconnected and facing the front part of the necktie and being wholly on the front face of the lining throughout the knot-forming area of the necktie, said stitching also comprising longitudinally extending portions disposed rearwardly of the lining and on both sides of the longitudinal axis of the necktie and laterally spaced from said axis.

9. A necktie including a casing and a lining 30

each yieldably extensible longitudinally of the necktie, said casing having a row of stitching extending generally along the axis thereof and slidably passing through the longitudinal edges of said casing thereby connecting the same and forming a tube and said stitching also slidably passing through said lining, said row of stitching being disposed in the rear portions of the necktie, said stitching comprising successive longitudinally extending stitch sections and transverse stitch sections connecting the ends of adjacent longitudinal sections, said transverse stitch sections being within said tube adjacent the rear surface of the front portion of said casing and forwardly of the lining.

10. A necktie including a casing having an end portion, a resilient lining in said casing yieldably extensible longitudinally of the necktie, said lining having a row of stitching extending generally along the axis of the lining and slidably passing therethrough, said stitching comprising successive longitudinally extending stitch sections and transverse stitch sections connecting the ends of adjacent longitudinal sections, said transverse stitch sections being on the front face of the lining and within the casing, said stitching extending through both the lining and the casing.
